US00D760388S

(12) **United States Design Patent**
Slawson et al.

(10) **Patent No.:** **US D760,388 S**
(45) **Date of Patent:** **** Jun. 28, 2016**

(54) **MEDICAL DEVICE**

(71) Applicant: **Welch Allyn, Inc.**, Skaneateles Falls, NY (US)

(72) Inventors: **Steve Slawson**, Skaneateles Falls, NY (US); **John Haberstock**, Skaneateles Falls, NY (US)

(73) Assignee: **WELCH ALLYN, INC.**, Skaneateles Falls, NY (US)

(**) Term: **14 Years**

(21) Appl. No.: **29/498,120**

(22) Filed: **Jul. 31, 2014**

(51) **LOC (10) Cl.** **24-02**

(52) **U.S. Cl.**

USPC **D24/137**

(58) **Field of Classification Search**

USPC D24/137, 138, 150, 172; 351/218, 221, 351/205, 206; 606/4

CPC A61B 1/227; A61B 3/1208; H02J 7/0045; H01M 2/1055; H01M 10/46; H01M 2/1005

Primary Examiner — Wan Laymon

Assistant Examiner — Mark Booker

(57) **CLAIM**

The ornamental design for a medical device, as shown and described.

DESCRIPTION

FIG. 1 is a perspective view of a medical device showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

Broken lines shown immediately adjacent shaded areas represent bounds of the claimed design and unclaimed features. All other broken lines are directed to unclaimed features. The broken lines form no part of the claimed design.

1 Claim, 6 Drawing Sheets
